UNITED STATES PATENT OFFICE

LYSLE E. SWENSON, OF SANDY CITY, UTAH

DIRIGIBLE HEADLIGHT

Application filed July 30, 1930. Serial No. 471,742.

This invention relates to an improved dirigible headlight such as is used in association with motor vehicles, and it has more particular reference to a structural assembly characterized by a single spotlight on the forward portion of the vehicle turnable with the front wheels and having operating connection with the steering gear.

The purpose of the invention is to provide a simple and effective structural organization of appropriately selected details wherein the centralized dirigible headlight is movable on a vertical axis and designed to swing through a path or arc consistent with the motion of the front wheels, whereby to permit the beam of light to follow the motion of said wheels when making turns and traversing irregular highways, in such a manner as to promote safe driving.

The explicit elements and their particular arrangements and association will become more readily apparent from the following description and drawings.

In the accompanying drawings, in which like numerals are employed to designate like parts of the same:

Figure 1 is a fragmentary plan view of a portion of a vehicle chassis showing the supplementary dirigible headlight associated therewith as developed in accordance with the present inventive conception.

Figure 2 is a side view of the structure shown in Figure 1.

Figure 3 is a view in section and elevation through a portion of the operating means, the section being approximately on the plane of the line 3—3 of Figure 2.

Figure 4 is a section on the line 4—4 of Figure 1.

Figure 5 is a detail section on the line 5—5 of Figure 1.

Figure 6 is a cross section on the line 6—6 of Figure 1.

Figure 7 is a perspective view of a connecting link constituting a part of the operating means.

In Figure 2, the numeral 8 designates a part of the frame, and 9 a front brace bar. In addition, the numeral 10 represents the

pitman or rocker arm of the steering gear. These parts are conventional.

The headlight is adjustably supported, preferably on the center of the rod 9 and is here shown as embodying a box-like casing 11. This casing has an internal vertical bearing 12 receiving the spindle 13. This spindle or axle 13 is provided on its upper end with a horizontal carrier arm 14 from which the tiltable headlight 15 is suspended.

There is an operating arm 16 attached to the lower end of the axle 13 and this is moved in a limited arc through the medium of the operating connection between this arm and the pitman 10.

The numeral 17 designates generally a flexible shaft comprising a bendable housing 18 of tubular form and an internal wire 19 of requisite flexibility. The forward end of this wire is secured by a fastener 20 to the arm. The numeral 21 designates a sleeve secured by a bracket to the frame of the car. This sleeve receives the slidable rod 22 which is attached to the rear end of the wire 19.

The rear end of the rod 22 is slidable in a tubular guide 23 fixedly mounted on the frame. A clamp 24 is adjustably fastened on the intermediate part of the rod and this constitutes a connector for the operating link 25. The link 25 extends rearwardly and downwardly and is attached by an adjustable clamp 26 to the rocker arm or pitman 10.

It follows that as the part 10 is actuated through the medium of the steering wheel (not shown), the rod 22 and its companion wire 19 move as a unit in a reciprocatory manner so as to impart swinging motion to the headlamp 15. Thus, the lamp follows the line of travel of the front wheels through the medium of the automatic steering gear connection.

It is thought that persons skilled in the art to which the invention relates will be able to obtain a clear understanding of the invention after considering the description in connection with the drawings. Therefore, a more lengthy description is regarded as unnecessary.

Minor changes in shape, size, and rearrangement of details coming within the field

of invention claimed may be resorted to in actual practice if desired.

I claim:

In combination with a motor vehicle and
5 a head lamp located at the front thereof, a
casing attached to a front part of the ve-
hicle and having a vertically arranged tub-
ular bearing on the inner face of the front
10 wall, the bore of which opens out through
the top of the casing, with the lower end of
the bearing terminating short of the bottom
of the casing, a shaft rotatably supported in
said bearing, and having its ends projecting
15 therefrom, an arm connected to the upper
end of the shaft and located exteriorly of
the casing, means for attaching the lamp to
the free end of said arm, an arm connected
to the lower end of the shaft and located in
20 the casing, and operating means connected
with the latter arm for swinging the lamp in
an arc of a circle.

In testimony whereof I affix my signature.

LYSLE E. SWENSON.
